QUATERNARY IMIDAZOLIUM AND
IMIDAZOLINIUM BISULFITESJerome Green, Chicago, Ill., assignor to Nalco Chemical
Company, Chicago, Ill., a corporation of Delaware
No Drawing. Filed Mar. 3, 1960, Ser. No. 12,502

1 Claim. (Cl. 260—309)

This invention relates to quaternary ammonium compounds, and more particularly quaternary ammonium salts of unstable acids which do not exist in pure form.

Quaternary ammonium compounds comprise a class of organic nitrogen compounds of the general structure:

where R_1 , R_2 , R_3 and R_4 are organic groups of the same and/or different kind, and X is an anion, usually inorganic and most commonly a halide. (N may be a member of a ring in which case the generalized structure must be modified.)

Because of the method of synthesis which is most commonly used in the preparation of quaternaries, the anionic part of the compound is usually a halide. The usual reaction employed is as follows. (This reaction is merely exemplary and is not the only one which has been used.)

While a vast number of combinations of R_1 , R_2 , R_3 and R_4 are possible, only a comparatively few elements or groups of elements can constitute X in the compound R_4X in order for the latter to react in the manner indicated.

Thus, most quaternaries of commercial importance are halides, usually chlorides. For various reasons, many of these quaternaries are shipped as concentrated solutions in water or water-alcohol (e.g., isopropanol) solvent. Such solutions are highly corrosive to steel and shipment is ordinarily made in specially lined steel containers or in glass. Even when diluted to use concentrations (usually 0.1 percent and less), aqueous solutions may be objectionably corrosive. Attempts have been made to remedy this property of dilute solutions by using adjuncts such as sodium nitrite, sodium carbonate, and borax. Sodium nitrite has found most favorable acceptance for this purpose. Such corrosion inhibitors for the most part either are not compatible with or do not bring about a suitable reduction in corrosivity of highly concentrated quaternary ammonium halide solutions to a point where they can be shipped, stored and handled in contact with ordinary steel.

One of the objects of the present invention is to provide a new and improved quaternary salt wherein an objectionable or less desirable anionic part of a quaternary salt is replaced with an innocuous, beneficial or more desirable one. By the practice of the invention, quaternary halides can be converted to other salts whose solutions are non-corrosive and can therefore be shipped and used without special precautions in this respect.

Another object is to provide new and improved quaternary salts which exhibit novel properties. For example,

2

in the practice of the invention it is possible to prepare quaternary ammonium compounds in which the anionic part of the molecule is not limited to those heretofore common to such compounds, but is one which confers unique and more desirable characteristics to the compound.

A more specific object of the invention is to provide new and improved quaternary ammonium salts of unstable acids which cannot be isolated in pure form, as, for example, quaternary ammonium salts of sulfuric acid, carbonic acid and nitrous acid.

Another specific object is to prepare new and useful quaternary ammonium salts which are non-corrosive per se and are also effective to inhibit corrosion of metals such as iron and steel when dissolved in normally corrosive liquids which are brought into contact with said metals.

A still further specific object is to provide new and useful quaternary ammonium nitrites, bisulfites, or bicarbonates. Other objects will appear hereinafter.

In accordance with the invention quaternary ammonium salts containing a predetermined anion as the salt forming constituent are prepared by bringing together a solution of the quaternary ammonium salt dissolved in a solvent and an anion exchange resin which is insoluble in said solvent and contains an anion different from that of the dissolved quaternary ammonium salt. The invention is especially valuable for converting highly corrosive quaternary ammonium salts to substantially non-corrosive quaternary ammonium salts. Most of the known quaternary ammonium salts have been prepared in the form of their halides which are highly corrosive, and by the practice of the invention these quaternary ammonium salts are converted to quaternary ammonium salts containing non-corrosive anions, e.g., nitrite, which are not only non-corrosive per se but also have the valuable property of being useful as corrosion inhibiting additives in water, oil and other materials tending to produce corrosion of iron and other metals.

My invention provides quaternary ammonium salts of unstable acids which cannot be isolated in pure form, as, for example, sulfuric acid, carbonic acid, and nitrous acid. To illustrate, nitrous acid, carbonic acid, and sulfuric acid decompose readily upon even slight heating and thus cannot be isolated in pure form as the acid. By the practice of the invention new quaternary ammonium salts of such acids which have new and useful properties can be prepared.

The principle of the method of preparing the compounds of my invention is given by the following equation:

The following conditions preferably employed to carry out the preparation are:

(1) The insoluble anion exchanger is of the strongly basic type. The commercially available ones at present are of the quaternary ammonium type, e.g., those disclosed in U.S. Patents 2,591,573 and 2,614,099.

The exchanger may be placed in the desired salt form

by means well known to those skilled in the art of ion exchange. For example, the exchanger may be treated with an excess of a strong solution of an inorganic salt possessing the desired anion.

(2) The concentration and time of contact of the solution of QH and RA is great enough so that ion exchange will occur. The necessity for these conditions is well recognized and their selection is accomplished without difficulty. The selectivity or preference of the exchanger for one ion over another is important here. This selectivity characteristic is illustrated in an article entitled "Properties of Strongly Basic Anion Exchange Resins" by R. M. Wheaton and W. C. Bauman, Industrial and Engineering Chemistry, vol. 43, pages 1088 to 1093 (1951). The higher the K value the greater the preference of the exchanger for that anion as compared with chloride ion. For anions not shown, the general rule is that the higher the valence or negative charge the stronger it is preferred by the resin; the larger the anion, the less it is preferred. These are only rough generalizations. For certain types of anion exchangers, of which Nalcite SAR and SBR are examples, the selectivity of the exchanger for various anions is also dependent on the degree of cross-linking of the resin matrix structure. The nature of the solvent system may also be expected to affect selectivity characteristics.

In the practice of the invention, the soluble quaternary salt can be converted to a number of intermediate salts before the one desired is finally made. This can be done, for example, to decrease the difference in selectivity of the insoluble ion exchange resin for the two ions to be exchanged in the final step. Such a procedure illustrates the versatility of the process.

(3) The solvent system is such as to permit sufficient ionization of RA and QH for exchange to occur. This will usually be assured by the presence of relatively small amounts of water. At the same time the solvent system should not dissolve or attack RA and must dissolve QH and preferably QA. While solution of QA is not essential, the formation of a precipitate is likely to clog the resin bed or coat the resin particles and seriously impair the progress of the reaction.

Polar solvents such as alcohols (e.g., methyl alcohol, ethyl alcohol, isopropanol), glycols (e.g., ethylene glycol, diethylene glycol), ketones, aldehydes, and dioxane, can be used to advantage. The proportions of water and solvent will be dependent on the particular conditions which must be met. The organic solvents also have the advantage of reducing the viscosity of aqueous solutions of QH and QA. Evaporation of the solvent to obtain QA in solid form can be carried out, depending on the properties of QA, such as stability.

In general, simple monovalent anions (such as nitrite, for example), will form water-soluble salts with Q-. Quaternary salts from more complex and highly charged anions are less soluble in water, and organic solvent-water systems are advantageous in these cases.

(4) The temperature is limited only by considerations of stability of the system reactants, products, and solvent in the presence of each other.

(5) The operation can be carried out column-wise or batch-wise. The latter consists of bringing the insoluble resin and solution of QH into contact, separating the two, then bringing the solution into contact with fresh resin and repeating as often as required. Column operation is usually simpler and more efficient and is preferred.

The invention is especially applicable to the synthesis of quaternary ammonium compounds having the following structural formulae in which X represents an anion, more particularly an anion of an unstable acid such as HSO_3^- , HCO_3^- , NO_2^- , $\frac{1}{2}\text{SO}_3^-$, or $\frac{1}{2}\text{CO}_3^-$.

Class I

- 4
- (A) $\text{R}_1, \text{R}_2, \text{R}_3$ are methyl; R_4 is a saturated or unsaturated alkyl or alkenyl group having 8 to 18 carbon atoms.
 (B) R_1 and R_2 are methyl; R_3 and R_4 are the same as R_4 in I(A).
 (C) R_1 and R_2 are methyl; R_3 is benzyl; R_4 is a long chain alkyl or alkenyl group.
 (D) R_1, R_2 , and R_3 are methyl, R_4 is benzyl.
 (E) Composites of I(A) to I(D).

10 Class II

In the following formulae, R is hydrogen or saturated or olefinic unsaturated hydrocarbyl radical, preferably of 1-17 carbons; R_1 and R_2 are alkyl, alkenyl, hydroxy alkyl, amino alkyl, aryl, or aralkyl; R_3 and R_4 are hydrogen atoms, alkyl, alkenyl, aryl or aralkyl groups.

The nitrite, bicarbonate, bisulfite, carbonate, or sulfite quaternary salts herein disclosed have many useful applications. They may be employed in place of the chloride ion in quaternary salts to reduce corrosivity toward ferrous metals. They have bactericidal activity toward bacteria such as *Aerobacter aerogenes*, *Flavobacterium* and the like. The bisulfites, for example, are oxygen scavengers. The bicarbonates and carbonates can be used instead of the chloride or sulfate quaternary salts in pharmaceutical preparations.

The best mode contemplated for the practice of the invention will be further illustrated but is not limited by the following examples in which the quantities are stated in parts by weight unless otherwise indicated.

EXAMPLE I

This example relates to the use of ion exchange in preparing a new compound tridecyl benzyl hydroxyethyl imidazolinium nitrite having the following structural formula

The ion exchange resin used in Nalcite SBR, which is a styrene-divinylbenzene resin containing quaternary amine ion exchange groups in which three of the R groups are methyl groups. This resin consists of spherical materials of 20 to 50 mesh, cream to pale yellow in color, and containing about 40% water. The divinyl benzene content is approximately 7.5%. The total exchange capacity is approximately 1.2 equivalents per liter wet volume. The K values for this resin are described in the article by Wheaton and Bauman, *supra*, page 1090, Table II.

The resin is placed in a tube or column 52 inches long and 1.5 inches in diameter. The height of the resin bed is 38 inches, the bed area is 0.0084 square foot and the bed volume is 0.028 cubic foot.

The resin bed is regenerated with a 4% aqueous solution of sodium nitrite used at the rate of 13.8 pounds of sodium nitrite per cubic foot of resin. The flow rate during the regeneration is one gallon per minute per cubic foot, and the injection time for the regenerant is 12 minutes.

The regenerated bed is rinsed with 5 gallons of deionized water.

A 10% solution in water of tridecyl benzyl hydroxyethyl imidazolinium chloride is passed through the column of anion exchange resin at a flow rate of 3 gallons per minute per square foot.

The resultant product is an aqueous solution of trimethylbenzyl hydroxyethyl imidazolinium nitrite having the formula given above. This solution can be concentrated or used as such.

The anion exchange resin can be used until the nitrite ion therein has been substantially exhausted as shown by a substantial increase in the chloride concentration of the effluent from the column of resin.

The percentage conversion of the imidazolinium chlo-

ride to imidazolinium nitrite is shown by the following table:

Table I

5	Throughput		Chloride Concentration of Effluent p.p.m.	Percent Conversion
	ML./0.028 cu. ft.	Gal. cu. ft.		
10	500	4.9	206	97.5
	1,000	9.8	218	97.3
	1,500	14.8	243	97.0
	2,000	19.7	315	96.1
	2,500	24.6	315	96.1
	3,000	29.5	620	92.4

15 It will be observed that the breakthrough occurs between 2500 and 3000 ml. and at this point the percentage conversion decreases sharply.

20 After the breakthrough point has been reached, the exchange bed is rinsed with deionized water prior to back washing and regeneration with more sodium nitrite. This rinse water is used for making up additional quantities of the solution of imidazolinium chloride. In this manner, any of the imidazolinium chloride which has been retained by the anion exchanger resin is saved and used in the process thereby avoiding losses in the wash water.

EXAMPLE II

25 A 500 ml. portion of the 10% aqueous solution of the imidazolinium chloride described in Example I is mixed with 150 ml. of the nitrite regenerated anion exchange resin described in Example I for a minimum of 4 hours. The resultant solution and resin are then separated by vacuum filtration. The filtrate is treated in a similar manner with 150 ml of fresh nitrite regenerated anion exchange resin.

30 The percentage conversion is shown by the following table:

Table II

No. of Applications of SBR-NO ₂	Vol. of 10% Imidazolinium Chloride	Vol. of SBR-NO ₂ , ml.	Contact Time, hrs.	Chloride Concentration of Filtrate, p.p.m.	Percent Conversion
45 0	500			8120	
1		150	1 20	2900	64.3
2		150	1 20	1210	85.1
3		150	1 20	534	93.4
4		150	1 20	315	96.1

50 ¹ Equilibrium is obtained in about 1-2 hours.

55 Example I illustrates the column or continuous method of preparation and Example II illustrates a batch method of preparation. The column method of operation is much more efficient and therefore is preferred.

EXAMPLE III

60 This example illustrates the application of the column method of Example I on a somewhat larger scale with a more concentrated solution of the imidazolinium chloride of Example I.

In this example the column consists of a tank 84 inches high and 12 inches in diameter. The anion exchange resin is the same as that used in Example I and the bed volume is 4 cubic feet.

65 The regeneration of the anion exchange resin is carried out with a 4% aqueous solution of sodium nitrite at a rate of 10 pounds of sodium nitrite per cubic foot of resin. The flow rate during regeneration is 0.5 gallon per minute per cubic foot of anion exchange resin and the injection time is 50 minutes.

The anion exchange resin is rinsed with Chicago tap water at a flow rate of 0.5 gallon per minute per cubic foot of resin until the end point is 1 grain per gallon of chloride ion expressed as NaCl.

70 The same imidazolinium chloride used in Example I is

employed except that the concentration is 13.3% by weight in water. The flow rate through the anion exchange resin bed is 3 gallons per minute per square foot. The breakthrough point is approximately 50 grains per gallon of chloride ion expressed as NaCl.

The general procedure is as follows: the anion exchange resin initially in the chloride state is classified by back washing and allowed to settle. The freeboard volume is drained to bed level and the regeneration stated by passing the 4% sodium nitrite solution down-flow through the bed. Following the passage of the regenerant solution a rinse period using Chicago tap water is carried out until the chloride content of the effluent drops to approximately 1 grain per gallon as NaCl, determined titrimetrically.

The freeboard volume is again drained to bed level and the tridecyl benzyl hydroxyethyl imidazolinium chloride is introduced into the unit, filling the freeboard volume, and is passed down-flow through the anion exchanger bed displacing the void volume. When the quaternary ammonium nitrite begins to appear in the effluent, the stream is directed to collecting tanks and the effluent is collected until the chloride content reaches approximately 50 grains per gallon expressed as NaCl.

The imidazolinium chloride remaining in the unit at the conclusion of the run is displaced with tap water to a collecting tank and is used to prepare additional quantities of the imidazolinium chloride. When the bed is washed free of the imidazolinium chloride the anion exchange bed is again backwashed and regenerated as previously described. It is then ready for use in the preparation of an additional quantity of the imidazolinium nitrite.

EXAMPLE IV

The procedures described in Examples I, II and III are carried out employing a different anion exchange resin, such as Nalcite SAR. This resin is similar to Nalcite SBR except that one of the methyl groups of the ion exchange quaternary salt groups is replaced by hydroxyethyl making the resin somewhat less basic in nature. The K values of this resin are given in the paper by Wheaton and Bauman, *supra*, page 1090, Table III.

EXAMPLE V

The procedure is the same as Example I except that sodium bisulfite is substituted for sodium nitrite in chemically equivalent amounts. The product is tridecyl benzyl hydroxyethyl imidazolinium bisulfite.

EXAMPLE VI

The procedure is the same as Example I except that sodium bicarbonate is substituted for sodium nitrite in chemically equivalent amounts. The product is tridecyl benzyl hydroxyethyl imidazolinium bicarbonate.

Similarly other quaternary ammonium salts of acids which do not exist in isolated state can be prepared in the practice of the invention.

The invention is especially suitable for converting solvent-soluble quaternary ammonium halides into a quaternary ammonium salt having an anion other than a halogen atom and especially those having anions which render the resultant product non-corrosive.

Specific examples of quaternary ammonium nitrites, bicarbonates, and bisulfites in accordance with the invention are the following:

- (1) Octyl trimethyl ammonium bicarbonate
- (2) Di-(octyl) di-methyl ammonium bisulfite
- (3) Decyl trimethyl ammonium bisulfite
- (4) Di-(decyl) dimethyl ammonium nitrite
- (5) Dodecyl trimethyl ammonium nitrite
- (6) Di-(dodecyl) dimethyl ammonium bicarbonate
- (7) Tetradecyl trimethyl ammonium bisulfite
- (8) Di-(tetradecyl) dimethyl ammonium bisulfite
- (9) Hexadecyl trimethyl ammonium nitrite
- (10) Di(hexadecyl) dimethyl ammonium nitrite

- 8
- (11) Octadecyl trimethyl ammonium bisulfite
  - (12) Di-(octadecyl) dimethyl ammonium nitrite
  - (13) Octadecenyl trimethyl ammonium bicarbonate
  - (14) Di-(octadecenyl) dimethyl ammonium nitrite
  - (15) Octadecadienyl trimethyl ammonium nitrite
  - (16) Di(octadecadienyl) dimethyl ammonium bicarbonate
  - (17) 1,3-dimethyl-2-heptyl imidazolium bisulfite
  - (18) 1,2-dimethyl-3-heptyl imidazolium bisulfite
  - (19) 1-allyl-3-heptyl-2-methyl imidazolium bisulfite
  - (20) 1-benzyl-2-heptyl-3-methyl imidazolium nitrite
  - (21) 1-(2',4'-dichlorobenzyl)-2-heptyl-3-methyl imidazolium nitrite
  - (22) 1-heptyl-2-methyl-3-benzyl imidazolium bisulfite
  - (23) 1-heptyl-2-methyl-3-(2',4'-dichlorobenzyl) imidazolium bicarbonate
  - (24) 1,3-dimethyl-2-nonyl imidazolium nitrite
  - (25) 1-methyl-2-nonyl-3-ethyl imidazolium bicarbonate
  - (26) 1-methyl-2-nonyl-3-allyl imidazolium bisulfite
  - (27) 1-methyl-2-nonyl-3-benzyl imidazolium nitrite
  - (28) 1-decyl-2,3-dimethyl-imidazolium nitrite
  - (29) 1-decyl-2,3-dimethyl imidazolium bicarbonate
  - (30) 1-decyl-2-methyl-3-ethyl imidazolium bicarbonate
  - (31) 1-decyl-2-methyl-3-allyl imidazolium bisulfite
  - (32) 1-decyl-2-methyl-3-methyl imidazolium nitrite
  - (33) 1-decyl-2-methyl-3-alpha-phenyl imidazolium nitrite
  - (34) 1-decyl-2-methyl-3-benzyl imidazolium bisulfite
  - (35) 1-decyl-2-methyl-3-benzyl imidazolium bicarbonate
  - (36) 1-decyl-2-methyl-3-benxyl imidazolium bicarbonate
  - (37) 1-decyl-2-methyl-3-(4'-chlorobenzyl) imidazolium nitrite
  - (38) 1,3-dimethyl-2-undecyl imidazolium nitrite
  - (39) 1-methyl-2-undecyl-3-methallyl imidazolium nitrite
  - (40) 1-methyl-2-undecyl-3-benzyl imidazolium bisulfite
  - (41) 1-methyl-2-undecyl-3-(4'-nitrobenzyl) imidazolium bicarbonate
  - (42) 1-amyl-2-undecyl-3-methyl imidazolium bicarbonate
  - (43) 1-amyl-2-undecyl-3-benzyl imidazolium bicarbonate
  - (44) 1-tetradecyl-2,3-dimethyl imidazolium bisulfite
  - (45) 1-tetradecyl-2-methyl-3-benzyl imidazolium nitrite
  - (46) 1,3-dimethyl-2-heptyl imidazolinium bisulfite
  - (47) 1-methyl-2-heptyl-3-(2'-chlorobenzyl) imidazolinium nitrite
  - (48) 1-heptyl-2-methyl-3-benzyl imidazolinium nitrite
  - (49) 1-benzyl-2-methyl-3-octyl imidazolinium nitrite
  - (50) 1,3-dimethyl-2-nonyl imidazolinium bicarbonate
  - (51) 1-methyl-2-nonyl-3-methallyl imidazolinium nitrite
  - (52) 1-methyl-2-nonyl-3-benzyl imidazolinium bicarbonate
  - (53) 1-decyl-2,3-dimethyl imidazolinium bisulfite
  - (54) 1-decyl-2-methyl-3-benzyl imidazolinium nitrite
  - (55) 1-decyl-2-amyl-3-methyl imidazolinium bisulfite
  - (56) 1-methyl-2-undecyl-3-benzyl imidazolinium nitrite
  - (57) 1-amyl-2-undecyl-3-methyl imidazolinium nitrite
  - (58) 1-amyl-2-undecyl-3-benzyl imidazolinium bicarbonate
  - (59) 1-amyl-2-undecyl-3-(2'-chlorobenzyl) imidazolinium bisulfite
  - (60) 1-dodecyl-2,3-dimethyl imidazolinium bisulfite
  - (61) 1-dodecyl-2-methyl-3-benzyl imidazolinium nitrite
  - (62) 1-dodecyl-2-methyl-3-(4'-chlorobenzyl) imidazolinium bicarbonate
  - (63) 1-tetradecyl-2,3-dimethyl imidazolinium bicarbonate
  - (64) 1-tetradecyl-2-methyl-3-methallyl imidazolinium nitrite
  - (65) 1-tetradecyl-2-methyl-3-benzyl imidazolinium nitrite
  - (66) 1-benzyl-2-methyl-3-octadecyl imidazolinium nitrite
  - (67) Lauryl isoquinolinium bicarbonate
  - (68) Cetyl isoquinolinium bisulfite
  - (69) Lauryl isoquinolinium bicarbonate
  - (70) Di-coconut dimethyl ammonium nitrite
  - (71) Coconut trimethyl ammonium nitrite
  - (72) Alkyl (C_8H_{17} to $C_{18}H_{37}$) dimethyl-3,4-dichlorobenzyl ammonium nitrites and alkenyl (C_{16} to C_{20}) dimethyl ethyl ammonium nitrites in the ratio 5:1

(73) Di-isobutyl phenoxy ethoxy ethyl dimethyl benzyl ammonium nitrite having the formula

(74) Di-isobutyl cresoxy ethoxy ethyl dimethyl benzyl ammonium bicarbonate, monohydrate having the formula

(75) Alkyl dimethyl benzyl ammonium bisulfite having the formula

R=mixture of alkyl radicals C_8H_{17} - $\text{C}_{18}\text{H}_{37}$, principally $\text{C}_{12}\text{H}_{25}$

(76) N-soya-N-ethyl morpholinium nitrite

(77) Octadecenyl-9-dimethyl benzyl ammonium nitrite

(78) 1-dodecyl-4-benzyl pyridinium bicarbonate

(79) 1-methyl-2-ethyl piperidinium bisulfite

(80) 2-phenyl-3-alpha-naphthyl-5-N-undecyltetrazolium bicarbonate

(81) Methyl quinolinium nitrite

(82) Benzyl quinolinium bisulfite

(83) 1-(3,3-diphenylpropyl)-1-methyl pyrrolidinium nitrite

(84) Hexadecyl pyridinium bisulfite

(85) Benzyl trimethyl ammonium nitrite

A special class of new compounds prepared by the practice of the invention is the imidazolinium nitrites having the general formula

wherein R is hydrogen or a hydrocarbyl radical, preferably a higher aliphatic hydrocarbon radical containing 8 to 18 carbon atoms (e.g., nonyl, undecyl, tridecyl, pentadecyl, heptadecyl); R₁ and R₂ are alkyl, preferably methyl, ethyl, propyl, isopropyl, butyl or isobutyl, aryl, preferably phenyl, or tolyl, aralkyl, preferably benzyl, hydroxyalkyl, preferably hydroxyethyl, hydroxypropyl, or hydroxybutyl, aminoalkyl, preferably $-\text{C}_2\text{H}_4\text{NH}_2$, $-\text{C}_2\text{H}_4\text{NH.C}_2\text{H}_4\text{NH}_2$, or $-\text{C}_3\text{H}_6\text{NH}_2$, and R₃ and R₄ are hydrogen, lower alkyl (e.g., methyl, ethyl, propyl, butyl, isopropyl, isobutyl), aryl, preferably phenyl or aralkyl, preferably benzyl, said compounds containing atoms from the group consisting of carbon, oxygen, hydrogen and nitrogen. A preferred subclass of such compounds is one in which R is a higher aliphatic hydrocarbon radical, saturated or unsaturated, containing 8 to 18 carbon atoms, one of the radicals R₁ and R₂ is a benzyl group and the other is a lower aliphatic group containing not more than 4 carbon atoms, the remaining atoms being from the group consisting of nitrogen, oxygen and hydrogen, and R₃ and R₄ are hydrogen or lower alkyl groups.

The temperatures used in the process should be above the freezing point of the solvent and below temperatures at which the insoluble anion exchanger tends to decompose or lose its capacity. Ordinarily, the ion exchange reaction is preferably carried out at room temperatures around 20° C. but higher temperatures can be used, depending upon the stability of the insoluble anion exchange resin and that of the desired quaternary ammonium salt. Some of the anion exchange resins such as Nalcite SAR and Nalcite

SBR can be used for days at temperatures of 50° C. to 60° C. but become markedly less stable at temperatures

above 150° C. The stability of the insoluble resin also varies, depending upon the particular anion. The resins must be treated to introduce the desired anion into the

resin before a soluble quaternary ammonium salt dissolved in a solvent is brought into contact with the resin in the practice of the invention.

To illustrate the advantages of the invention, aqueous solutions of the quaternary ammonium salt used as a starting material in Example I, i.e., aqueous solutions of tridecyl benzyl hydroxyethyl imidazolinium chloride, are very corrosive to steel and therefore cannot be transported in ordinary steel drums but are normally transported in glass containers or carboys. However, aqueous solutions of the tridecyl benzyl hydroxyethyl imidazolinium nitrite produced as described in Example I are non-corrosive and can be transported in ordinary steel drums. This is of great importance from the practical standpoint. The addition of corrosion inhibitors such as disodium orthophosphate, monosodium orthophosphate, sodium nitrite, sodium carbonate, sodium polyphosphates, sodium silicates, and sodium tetraborate to quaternary ammonium halides in order to decrease the corrosive action of such halides is not ordinarily satisfactory because many well known corrosion inhibitors either are ineffective to prevent corrosion or cause precipitates which contaminate the product and are undesirable. Many of the ordinary corrosion inhibitors are incompatible with the quaternary ammonium salt because of the formation of these precipitates. A material is considered to be incompatible when the amount of precipitate formed is greater than that formed in the untreated solution. As an example, a 10% solution of tridecyl benzyl hydroxyethyl imidazolinium chloride was treated with various well known types of inorganic corrosion inhibitors in various amounts and the resultant solution examined for precipitation after 24 hours. Static corrosion tests were run on some of these solutions at room temperatures (20° C.). Two mild steel panels, one inch by two inches, were suspended in 200 ml. of the solution. A weighed panel was completely immersed and another was partially immersed. The corrosion rate was determined for the totally immersed panel. The water line attack was observed on the other panel. The results were as follows:

	Treatment	Corrosion Rate in Mils per Year	Degree of water-line Attack	Precipitate Formed
60	None	3.5	Severe	
	1,200 p.p.m. Na_2HPO_4 + 1,200 p.p.m. $\text{Na}_2\text{PO}_4 \cdot \text{H}_2\text{O}$	3.1	mild	yes
	660 p.p.m. Na_2HPO_4 + 600 p.p.m. $\text{Na}_2\text{SiO}_3 \cdot 5\text{H}_2\text{O}$	2.8	do	yes
	150 p.p.m. Na_2HPO_4 + 150 p.p.m. $\text{Na}_2\text{PO}_4 \cdot \text{H}_2\text{O}$			
65	300 p.p.m. Na_2HPO_4 + 300 p.p.m. $\text{Na}_2\text{PO}_4 \cdot \text{H}_2\text{O}$ + 200 p.p.m. $\text{Na}_2\text{SiO}_3 \cdot 5\text{H}_2\text{O}$	3.8	mild	yes
	600 p.p.m. Na_2HPO_4 + 600 p.p.m. $\text{Na}_2\text{PO}_4 \cdot \text{H}_2\text{O}$ + 1,200 p.p.m. NaNO_2	8.0	severe	yes
	2,400 p.p.m. NaNO_2 (pH 6.5)	0.3	do	no
70	1,200 p.p.m. NaNO_2 (pH 7.0)			
	1,200 p.p.m. Na_2CO_3 + 2,400 p.p.m. NaNO_2 (pH 7.0)			
	2,400 p.p.m. Na_2CO_3 (pH 8.0)			yes
	800 p.p.m. $\text{Na}_2\text{P}_2\text{O}_10$	3.5	mild	yes
	200 p.p.m. $\text{Na}_2\text{SiO}_3 \cdot 5\text{H}_2\text{O}$	2.5	severe	yes
	200 p.p.m. $\text{Na}_2\text{B}_4\text{O}_7 \cdot 10\text{H}_2\text{O}$			yes

It will be noted that most of the treatments used were incompatible with the quaternary ammonium chloride at the particular concentrations of each employed. Furthermore, although 2400 parts per million of sodium nitrite decreased the corrosion rate of a completely immersed specimen to a satisfactory level, the attack at the water line was severe. This line is present in any partially filled container. On the other hand, the nitrite of Example I produced no attack at the water line as shown by the following comparative test results between the tridecyl benzyl hydroxyethyl imidazolinium chloride and the nitrite carried out in the same manner:

Test No.	Composition of Solution (10% by wt.)			Totally Immersed Specimen		Partially Immersed Specimen		
	Percent Cl- Form by Volume	Percent NO ₂ - Form by Volume	Duration of Test, days	Weight Loss, mg.	Rate of Attack, MPY	Weight Loss, mg.	Rate ¹ of Attack, MPY	Magnitude of Water Line Attack
1-----	100	0	11	41.7	2.22	83.7	3.56	Faint.
2-----	98.75	1.25	11	64.7	3.44	107.8	4.58	Do.
3-----	93.75	6.25	11	93.3	4.96	137.0	6.49	Moderate.
4-----	87.5	12.5	11	132.1	7.03	158.0	7.47	Do.
5-----	75.0	25.0	11	20.6	1.10	121.3	5.74	Very heavy.
6-----	50.0	50.0	11	1.6	0.09	20.9	0.99	Concentrated at one point.
7-----	25.0	75.0	11	1.9	0.10	9.6	0.43	None.
8-----	0	100	17	0.7	0.02	1.0	0.03	Do.

¹ Only the area exposed to the test solution was used in calculating the rate of attack.

Not only is the compound of Example I less corrosive to steel containers than the tridecyl benzyl hydroxyethyl imidazolinium chloride but it also acts as an inhibitor when used in small amounts to retard or prevent corrosion when added to burning oils, diesel fuels, kerosene, gasoline, and crude petroleum coming from the well, and functions to prevent attack of oil and gas well equipment when added in "down-the-hole" treatments.

Concentrations of 4 to 16 parts per million of tridecyl benzyl hydroxyethyl imidazolinium nitrite killed *Aerobacter aerogenes* and two species of *Flavobacterium* after one hour of contact.

The invention is not limited to the employment of a particular insoluble anion exchange body. However, the use of a strongly basic insoluble anion exchange body has the distinct advantage that the soluble quaternary ammonium salt, for example, a soluble quaternary ammonium chloride, can be converted directly to a quaternary ammonium salt having a different anion. The expression "strongly basic anion exchange resin" is employed herein to describe an anion exchange resin which is capable of converting salts directly to hydroxides. Thus, a strongly basic anion exchange resin is capable of converting an aqueous solution of sodium chloride directly to an aqueous solution of sodium hydroxide.

In general, a strongly basic ion exchange resin is one which on titration with hydrochloric acid in water free from electrolytes has a pH above about 7.0 when the amount of hydrochloric acid added is one-half of that required to reach the inflection point (equivalence point). A weakly basic ion exchange resin under the same conditions has a pH below about 7.0 when one-half of the acid required to reach the equivalence point has been added. Weakly basic anion exchange resins do not function to accomplish this result but weakly basic anion exchange resins can be used to effect the end result by an indirect procedure.

One of the difficulties in using weakly basic anion exchange resins in the practice of the invention is the introduction into the resin of the anion which it is desired to exchange. If the weakly basic resin is in the hydroxide form, another anion can be introduced into the resin by regenerating it with an acid. For example, the chloride anion can be introduced by treating the hydroxide form of the resin with hydrochloric acid. The nitrite anion can be introduced by treating the hydroxide form of the resin with nitrous acid. However, the hydroxide form of the

resin cannot be treated directly with a salt in order to introduce the anion. In order to introduce anions of suitable acids such as the nitrite anion into a weakly basic anion exchange resin, the hydroxide form of the resin is first converted to the chloride form by treatment with hydrochloric acid and the chloride form of the resin is then converted to the nitrite form by treatment with an aqueous solution of sodium nitrite.

Another disadvantage of the weakly basic resins is the tendency of their salt forms to hydrolyze to the hydroxide form. This makes it desirable when using such anion exchange resins to operate under acidic conditions. The

use of acidic conditions for optimum results is not a limitation of the strongly basic anion exchange resins.

In order to obtain the optimum results the affinities of the insoluble resin for the respective anions to be exchanged between insoluble resin and the dissolved quaternary ammonium salt, on the one hand, and between the exhausted insoluble resin and the dissolved regenerant on the other are important in determining the efficiency of the process described in this invention. If these affinities are greatly different, the displacement from the resin of the anion for which it has the greater affinity by the one for which it has the lesser affinity will be accomplished with difficulty. While this difficulty can be overcome in part by appropriate selection of concentrations of dissolved quaternary ammonium salt or regenerant, it is preferable in the operation of this invention that the affinities of the resin for the anions to be exchanged do not differ by more than ten-fold, as measured by their selectivity constant (K values). In other words, the ratios of the selectivity constants of the anions to be exchanged should be within the range of 10:1 to 1:10. Greater differences are permissible but cause decreasing efficiencies either in conversion of the quaternary ammonium salt or insoluble resin to the salt form desired. For example, Nalcite SAR and Nalcite SBR have very much greater affinities for salicylate ions than chloride ions. The passage of a solution of sodium salicylate through a bed of either of these resins in the chloride form converts the resin to the salicylate form with extreme ease. However, when a solution of quaternary ammonium chloride is passed through a bed of the salicylate form of the resin only a small percentage of exchange occurs. On the other hand, Nalcite SAR and Nalcite SBR have about the same affinities for chloride ions as for nitrite ions and the percentage of exchange both in regeneration of the resin by sodium nitrite and in exhaustion of the resin by the aqueous solution of quaternary ammonium chloride is high.

Examples of weakly basic anion exchange resins which can be employed in the practice of the invention are those described in U.S. Patents 2,582,098, 2,597,439 and 2,597,491. Examples of strongly basic anion exchange resins which can be employed in the practice of the invention are those disclosed in U.S. Patents 2,591,573, 2,597,440, 2,597,494, 2,614,099, 2,630,427, 2,632,000 and 2,632,001.

The strongly basic insoluble anion exchange resins

which are preferably employed for the purpose of the invention are reaction products of a tertiary alkyl amine and a vinyl aromatic resin having halo methyl groups attached to aromatic nuclei in the resin. Another class of anion exchange resins suitable for the practice of the invention are the reaction products of tertiary carbocyclic or heterocyclic amines and vinyl aromatic resins having halo methyl groups attached to aromatic nuclei in the resin. The vinyl aromatic resins employed as starting materials in making the anion exchange resins employed in the preferred practice of the invention are the normally solid benzene-insoluble copolymers of a monovinyl aromatic compound and a polyvinyl aromatic compound containing from 0.5 to 40% by weight, preferably from 0.5 to 20% by weight of the polyvinyl aromatic compound chemically combined with the monovinyl aromatic compound. Examples of suitable monovinyl aromatic compounds are styrene, alpha methyl styrene, chlorostyrenes, vinyl toluene, vinyl naphthalene, and homologues thereof, capable of polymerizing as disclosed, for example, in U.S. Patent 2,614,099. Examples of suitable polyvinyl aromatic compounds are divinyl benzene, divinyl toluene, divinyl xylene, divinyl naphthalene and divinyl ethyl benzene. These resins are halo methylated as described, for instance, in U.S. Patent 2,614,099, preferably to introduce an average of 0.2 to 1.5 halo methyl groups per aromatic nucleus in the copolymer and then reacted with a tertiary amine to introduce a quaternary ammonium anion exchange group. Examples of suitable tertiary amines are trimethyl amine, triethyl amine, tributyl amine, dimethyl propanol amine, dimethyl ethanol amine, methyl diethanolamine, 1-methylamino-2,3-propane diol, diethyl ethanolamine, and homologues thereof.

The weakly basic resins are prepared in a similar manner except that primary and secondary amines are reacted with the halo alkylated resin. Examples of such amines are methyl amine, dimethyl amine, N-butyl amine, dibutyl amine, isobutyl amine, aniline, benzidines, toluidines, xylidines, alpha and beta naphthalene, naphthalene diamines, benzyl amine, dibenzyl amine, ethylenediamine, cyclohexylamine, dicyclohexylamine, diethylene triamine, triethylene tetramine, tetraethylene pentamine, propylene diamine, dipropylene triamine, and homologues thereof. The anion exchange resins can also be prepared by halogenating the molecule of the resin and then introducing an anion exchange group as described in U.S. Patent 2,632,000.

Throughout the specification and claim the terms "alkyl" and "alkenyl" are intended to define an aliphatic hydrocarbon radical, either saturated or unsaturated, branched chain or straight chain, for example, methyl, ethyl, propyl, butyl, amyl, hexyl, heptyl, octyl, nonyl, decyl, undecyl, lauryl, tridecyl, myristyl, cetyl, stearyl, propenyl, allyl, oleoyl, linoleyl, ricinoleyl, linolenyl, and homologues thereof.

The term "aminoalkyl" refers to an alkyl group containing an amino substituent substituted for at least one hydrogen atom of an alkyl group.

The term "hydroxylalkyl" refers to an alkyl group containing a hydroxyl group substituted for at least one hydrogen atom (e.g., hydroxyethyl, hydroxypropyl, and homologues thereof.)

The term "aryl" is used herein to define aromatic carbocyclic groups derived from aromatic hydrocarbons by the removal of one hydrogen atom, for example, phenyl, naphthyl, tolyl, xylyl, and homologues thereof.

The term "aralkyl" is used to define a radical derived by the removal of a hydrogen atom from an aliphatic side chain attached to an aromatic hydrocarbon, for example, benzyl, phenyl ethyl, phenyl propyl, cinnamyl, and homologues thereof.

The term "hydrocarbyl" is used to describe a group which is a monovalent hydrocarbon group.

The selectivity constants for various anions can be determined as described by Wheaton and Bauman, *supra*, for determination of the equilibrium value K_c .

The present application is a continuation-in-part application of my copending application, Serial No. 546,857, filed February 13, 1956, which in turn is a continuation-in-part of my copending application Serial No. 367,767, filed July 13, 1953, both of which are now abandoned and are incorporated herein by reference as fully as if they had been set forth in their entirety.

The invention is hereby claimed as follows:

An aqueous solution of a quaternary ammonium compound selected from the group consisting of

25 (I)

30 and

(II)

35

wherein R is selected from the group consisting of hydrogen, a saturated hydrocarbon group of 1-17 carbon atoms and an olefinically unsaturated hydrocarbon group of 1-17 carbon atoms, R₁ is selected from the group consisting of lower alkyl, lower alkenyl, and monohydroxy lower alkyl, and R₂ is a member selected from the group consisting of benzyl and lower alkyl.
